UNITED STATES PATENT OFFICE

2,660,751

CUSHIONING BUMPER

Douglass R. Falkenberg, Lakewood, Ohio

Application March 3, 1950, Serial No. 147,369

4 Claims. (CL. 16—122)

1

The invention relates to bumpers, and is illustrated herein by drawings and a description showing, first, the application thereof to pull-weights and its use in connection with cords that are utilized for traversing and/or raising and lowering draperies.

A second application of the invention relates to its use as a sleeve for door knobs.

The claims of the instant application are limited to the improvements in bumpers which serve as pull-weights.

The objects of the invention are to provide an article of the character stated which will not break windows or mar walls and woodwork, which is noiseless, which is of ornamental and pleasing appearance, and which can be manufactured at a cost which permits sale thereof at an economical price.

Insofar as the application of the principle of the invention to pull-weights is concerned, the merits of the invention are of particular value since pull-weights of the character stated have become of greatly increased size and weight for many of the draperies with which they are now used.

The annexed drawings and the following description set forth in detail certain means illustrating the improvements in bumpers, such disclosed means constituting, however, only a few of the many forms in which the principle of the invention may be embodied.

In said annexed drawings:

Figure 1 is an elevation of one form of the improved pull-weight;

Figure 2 is an axial section taken in the plane indicated by the line 2—2, Figure 1;

Figure 3 is a section taken in the plane indicated by the line 3—3, Figure 1;

Figure 4 is a top plan of the pull-weight shell or cover;

Figure 5 is an elevation, partially in section, showing the pull-weight impinging upon a window or wall;

Figure 6 is an elevation of a second form of the improved pull-weight;

Figure 7 is a top plan of the shell of Figure 6;

Figure 8 is an axial section, taken in the planes indicated by the line 8—8, Figure 7;

Figure 9 is an elevation, partially in section, of a third form of the improved pull-weight;

Figure 10 is a side elevation of a form of the improved bumper applicable for use with door knobs, a door plate and a fragmentary portion of a door being also shown in the figure; and

Figure 11 is an axial section of the bumper

shown in Figure 10, the door knob and its associated elements being shown in elevation, the section being indicated by the line 11—11, Figure 10.

Referring to the annexed drawings in which the same parts are designated by the same respective numbers in the several views, and particularly first referring to the form of the pull-weight shown in Figures 1 to 5, a heavy bulbous core of the improved pull-weight, preferably a die-cast body, comprises an elongated upwardly tapered tubular metal element 1, preferably zinc, having a flaring shoulder 2 somewhat removed from its larger end whence the core continues in an outwardly convex formation 3 to a substantially plane apertured lower face 4, as shown in Figure 2. The hole 5 in this tubular core accommodates a length of cord 6 having an end knot 6¹ which is disposed in a lower end larger cross-sectional part 5¹ of the hole 5, thus providing for suspension of the pull-weight from the cord 6. The lower outer end of the larger part 5¹ of the hole 5 forms the aperture in the face 4 of the core 1. The cord 6 at its other end is connected to the drapery traversing mechanism or utilized for raising and lowering draperies, as is well understood in the art. The hole 5 is made in the metal element 1 by an arbor or any other suitable device for forming the hole during the casting of the metal core.

Conforming to the exterior surface of the metal core 1 is a shell or cover 8 having a depending skirt spaced at its lower end from the lower part 3 of the metal core. As hereinafter fully explained, the skirt comprises an inner portion and a spaced flared outer flexible portion at the lower part of the cover. Preferably the shell or cover 8 is molded to the metal core 1 and is formed of a flexible and cushioning plastic such as polyethylene or other similar oily and rubber-like plastic which is non-soluble. The shell has an elongated tapered upper end portion conforming to the end portion 1 of the metal core and an enlarged lower end portion providing the flexible cushioning bumper effect. Preferably the enlarged lower end of the shell 8 is of elongated inverted U-like axial section having the transversely-spaced cover skirt portions 9 and 10, as shown in Figure 2, of which portion 9 is molded to the core part 3 and spaced portion 10 is a flared outer flexible part. The entire pull-weight comprised of the heavy core 1 and the light resilient cover 8 is of generally cone-like formation.

The portion 3 of the metal core and the inner

2

leg 9 of the U-shaped end of the molded plastic shell have bottom inwardly-turned peripheral edge portions 3¹ and 9¹, of annular formation, of which 9¹ is molded closely around 3¹.

Referring to the form of the improved pull-weight shown in Figures 6, 7, and 8, the heavy core 12, preferably metal, is of generally elliptical axial cross-section, and is formed at its lower end with an inwardly extending peripheral flange 12¹, thus providing a bottom recess 13. The core 12 is formed with an opening therethrough from end to end through which passes the operating cord 15 having a knotted lower end 15¹ seated in the recess 13. A shell or cover 16 of flexible cushioning plastic is molded around the core 12 and has an inturned lower end flange 17 closely engaging the inner face of the core flange 12¹ and providing a socket into which the knotted end 15¹ of the cord 15 extends.

Branching from the plastic shell 16, adjacent its lower end, is a flaring skirt portion 18 of subdivided scalloped formation to provide spaced petals 19, Figure 7.

Referring to the form of the improved pull-weight shown in Figure 9, substantially the same structure is shown as in Figures 6, 7, and 8 except that the flaring skirt 20 of the device shown in Figure 9 is an unbroken structure and is elongated at its outer end into an upturned annular peripheral rim 21.

The devices shown and described serve effectively as pull-weights inasmuch as they provide a grip and keep the operating cords taut. Furthermore, the outer leg or skirt 10 of the molded plastic shell shown in Figure 2, and the petals 19 shown in Figure 7, and the upturned peripheral edge portion 21 shown in Figure 9, provide resilient structures which are substantially noiseless upon impact with windows, walls, and the like, and which flex in and absorb any impact of the pull-weights, when the latter are swinging or disturbed for any reason, without marring or breaking such window, wall, woodwork or other object 11 with which the pull-weights come into contact, as shown in Figure 5.

The bumper or cushion formed of polyethylene or similar oily and resilient plastic changes its shape upon impact but does not squeeze together into a smaller space. All of the different forms of applicant's pull-weight provide space for the action of the cushioning bumper which is a flexing action and not one in which the total cubic content of the impacted rim is substantially decreased by the impact.

The form of the improved bumper shown in Figures 10 and 11 is applicable for use with door knobs to provide a non-marring effect such as has been described with reference to the pull-weight formation shown in Figures 1 to 9.

For door knob use, the knob 23 itself is the hard core. As shown in Figure 11, these knobs 23 are

usually provided with an end shoulder 23¹ by means of which they are secured to the door bolt actuating mechanism, the shoulder 23¹ abutting the outer end of a central tubular flange portion 24¹ of the door plate 24 secured to the door 25.

The improved bumper is a sleeve closely engaged with the outer surfaces of the knob 23, shoulder 23¹, and flange 24¹, and has a main body portion 26 surrounding the door knob 23 and an extended collar 27 surrounding the shoulder 23¹ and the flange 24¹. This sleeve is preferably formed of semi-rigid plastic material having flexible characteristics and is extended at its outer end into an enlarged annular formation 28 which takes the impact when the door knob 23 strikes adjacent walls, etc., and thus provides the noiseless and non-marring effects. In the form of flexible bumpers shown in Figures 10 and 11 the annular formation 28 itself provides the space in which the flexure may take place. Preferably, the inner surface of the body portion 26 of the bumper is recessed to form a seat 26¹ with which the door knob 23 snugly engages.

What I claim is:

1. In a pull-weight for a drapery and other like cord-operated mechanism formed for swinging suspension and having a heavyweight bulbous body, the improvement comprising a lightweight relatively thin resilient shell enclosing said body, the lower portion of said shell being divided into an inner skirt portion and an outer flexible skirt portion spaced from said inner skirt portion, said inner skirt portion embracing and fitting over the lower end of the body and said outer flexible skirt portion serving as a bumper for the pull-weight.
2. A pull-weight, as characterized in claim 1, in which the shell is formed of an oily and resilient plastic of the order of polyethylene.
3. A pull-weight, as characterized in claim 1, in which the body is tubular to provide a suspending-cord hole, and in which the inner skirt portion also embraces and fits over the bottom face of the body and is extended into the latter to form an enlarged cord recess aligned with the cord hole.
4. A pull-weight, as characterized in claim 1, in which the outer skirt portion is turned upwardly at the bottom to form a flaring peripheral rim.

DOUGLASS R. FALKENBERG.
